PILE RUG

John J. Matwin, and John E. Taylor, Greenville,
S. C., assignors to Belrug Mill, Inc., Greenville,
S. C., a corporation of South Carolina

Application December 9, 1947, Serial No. 790,576

3 Claims. (Cl. 139—397)

1

Our invention relates to pile fabric, such as rugs or the like.

An important object of the invention is to provide a pile fabric or rug having a uniform weave and appearance throughout.

A further object of the invention is to provide a cut pile fabric wherein the tufts are formed in pairs so that the pile will contain an increased number of tufts, imparting to the pile the proper body, enhancing the appearance of the rug and prolonging its life.

A further object of the invention is to provide a cut pile fabric or rug which has a strong and stout back.

A further object of the invention is to provide a cut pile fabric or rug so constructed that the method of weaving is simplified.

A further object of the invention is to provide a cut pile fabric which may be run back straight to the take-up roller on the loom and which will have the transverse take-up or shrinkage eliminated, to some extent.

Other objects and advantages of the invention will be apparent during the course of the following description.

In the accompanying drawings, forming a part of this application, and in which like numerals are employed to designate like parts throughout the same,

Figure 1 is a fragmentary perspective view, partly diagrammatic, showing three warpwise rows of tufts.

Figure 2 is a longitudinal section through the rugs before the same are severed, showing the formation of the tufts, the warps being omitted for the purpose of clearness; and,

Figure 3 is a fragmentary plan view of the woven fabric rug upon an enlarged scale.

Two fabrics or rugs are woven at the same time, in opposed relation, and the pile or tufts are severed, as is well known. This is the conventional practice, as shown in patents such as 2,306,390 and 2,306,405.

In accordance with our invention, upper and lower rugs are woven, which are designated A and B, Figure 2. Each rug comprises a woven back or body portion including spaced filling threads 1 to 13 inclusive, and longitudinal warps 14 and 15. The warps 14 are tight and are arranged in pairs, and the warps 15 are slack and are arranged in pairs. The pairs of tight warps 14 are interwoven with the filling threads 1 to 13. Each pair of warps 14 passes outwardly of and about the filling thread 1 and inwardly of and about the filling thread 2, and this alternate

2

arrangement continues with the remaining filling threads throughout the length of the fabric. Each pair of slack warps 15 passes inwardly and about the filling thread 1 and outwardly and about the filling thread 2, and this alternate arrangement continues with respect to the remaining filling threads throughout the length of the fabric. The warps and filling threads are thus interwoven. The tight warps 14 are arranged in pairs, and the slack warps 15 are arranged in pairs, and the pairs of slack warps occur between the pairs of tight warps. Further, the use of alternately arranged pairs of tight warps and pairs of slack warps eliminates to some extent the transverse take-up or shrinkage, that would ordinarily occur.

The numerals 16 and 16' designate two pairs of pile threads associated with each pair of tight warps 14, to form W-shaped tufts 16a between the warp threads in the pair. The two pairs of pile threads 16 and 16' extend between the tight warps in the pairs of transversely aligned warps 14 of the opposed rugs, A and B, during the weaving process. The interwoven warps and filling threads form the body portion or back of each rug. In connection with the back of rug A, each pair of pile threads 16 passes outwardly of and about the filling thread 2 of rug A, inwardly of and about the filling thread 3 of rug A, and outwardly of and about the filling thread 4 of rug A, and then crosses over to rug B and passes outwardly of and about the filling thread 6 of rug B, inwardly of and about the filling thread 7 of rug B, and outwardly of and about the filling thread 8 of rug B. This pair of pile threads 16 then crosses over to rug A and passes outwardly of and about the filling thread 10 of rug A, inwardly of and about the filling thread 11 of rug A, and outwardly of and about the filling thread 12 of rug A. In connection with the rug B, each pair of pile threads 16' passes outwardly of and about the filling thread 2 of rug B, inwardly of and about the filling thread 3 of rug B, and outwardly of and about the filling thread 4 of rug B, and then crosses over to rug A. This pair of pile threads 16' then passes outwardly of and about the filling thread 6 of rug A, inwardly of and about the filling thread 7 of rug A, and outwardly of and about the filling thread 8 of rug A, and then crosses over to rug B. In rug B, this pair of pile threads 16' passes outwardly of and about the filling thread 10 of rug B, inwardly of and about the filling thread 11 of rug B, and outwardly of and about the filling thread 12 of rug B. This

same arrangement of the pile threads 16 and 16' is continued beyond the filling threads 1 and 13, throughout the entire length of the fabric, as is obvious. The two pairs of pile threads 16 and 16' provide W-shaped portions, having sides 17 which cross. These W-shaped portions form the W-shaped tufts 16a, when severed, and are arranged within the opposed pairs of tight warps 14. The pair of pile threads 16 forms spaced W-shaped portions in each rug, and the pair of pile threads 16' forms spaced W-shaped portions in each rug, alternately arranged with the other W-shaped portions. When the crossed portions 17 are severed at their line of crossing, in separating the rugs, the pairs of W-shaped portions form the W-shaped tufts 16a, having ends 17', as shown.

Disposed between the crossed sides 17 are single filling threads 1, 5, 9, and 13. The pairs of W-shaped tufts 16a, Figure 1, are arranged in longitudinal rows, and one longitudinal row is between the tight warps 14 of each pair. The pairs of W-shaped tufts 16a are also disposed in spaced transverse rows. A single filling thread is arranged between each pair of transverse rows of W-shaped tufts 16a, and is equidistantly spaced therefrom. It is to be noted that the pairs of W-shaped tufts 16a in each transverse row, Figure 1, are carried by a group of three filling threads, and extend outwardly of and about the outer filling threads in the group and inwardly of and about the intermediate filling thread in the group. The ends 17' of the W-shaped tufts 16a in two adjacent transverse rows are disposed upon opposite sides of a single filling thread arranged between such transverse rows, as stated.

The arrangement of the W-shaped tufts is uniform throughout the rug, both transversely and longitudinally. It is to be noted that there are four warps between the adjacent longitudinal rows of W-shaped pairs of tufts 16a, two tight warps 14 and two slack warps 15. This provides two warps adjacent to the two pairs of pile threads 16 and 16', one warp extending up and the other down. This arrangement of the two warps adjacent to the opposite sides of the two pairs of pile threads 16 and 16' prevents the pairs of pile threads from roving.

As shown in Figure 1, the completed fabric or rug B is uniform. The body portion or bottom of the rug has woven therein the transverse rows of W-shaped tufts 16a, and these W-shaped tufts are also arranged in longitudinal rows. An advantage in having the pairs of W-shaped tufts in transverse rows and in equidistantly spaced longitudinal rows is that the weaving is simplified. The advantage in having the W-shaped tufts 16a in pairs is that a proper body is imparted to the pile and it is given an attractive appearance, without complicating the weaving process. A further advantage in having four warp threads between two longitudinal sets of W-shaped tufts 16a is that the back is made stronger and firmer. A pair of slack warps 15 and a pair of tight warps 14 constitute a group of 4, which group is passed through the same space in the reed, and this is true of the pair of pile threads 16 or 16'.

Having thus described our invention, we claim:

1. A rug or the like, comprising a back including alternately arranged pairs of tight warps and pairs of slack warps and filling threads interwoven with the pairs of tight warps and the pairs of slack warps, and generally W-shaped tufts,

each generally W-shaped tuft including a pair of threads, the generally W-shaped tufts being arranged in longitudinal rows, a longitudinal row being disposed between the warps in each pair of tight warps, the generally W-shaped tufts being also arranged in transverse rows, the tufts in each transverse row being carried by a group of three filling threads and passing outwardly of and about the outer filling threads in the group and inwardly of and about the intermediate filling thread in the group, the groups being spaced, and a single filling thread arranged between adjacent groups and between the adjacent transverse rows of tufts.

2. A rug, or the like, comprising a back including alternately arranged pairs of tight warps and pairs of slack warps and filling threads interwoven with the pairs of tight warps and pairs of slack warps, and generally W-shaped tufts, each generally W-shaped tuft including a pair of threads, the generally W-shaped tufts being arranged in longitudinal rows which are equidistantly spaced, all of the longitudinal rows being disposed between the warps in the pairs of tight warps, the generally W-shaped tufts being also arranged in transverse rows which are equidistantly spaced, the tufts in all of the transverse rows being carried by groups of three filling threads, all of the generally W-shaped tufts passing outwardly of and about the outer filling threads in the groups, and inwardly of and about the intermediate filling threads in the groups, and single filling threads arranged between all groups of three filling threads and arranged between all of the transverse rows of generally W-shaped tufts.

3. A rug or the like, comprising a back including alternately arranged pairs of tight warps and pairs of slack warps and filling threads interwoven with the pairs of tight warps and the pairs of slack warps, and generally W-shaped tufts, each generally W-shaped tuft including a plurality of threads, the generally W-shaped tufts being arranged in longitudinal rows, a longitudinal row being disposed between the warps in each pair of tight warps, the generally W-shaped tufts being also arranged in transverse rows, the tufts of each transverse row being carried by a group of the filling threads including an intermediate filling thread and outer filling threads and such tufts passing outwardly of and about the outer filling threads in the group and inwardly of and about the inner filling thread in the group, the groups being spaced, and at least one filling thread being arranged between adjacent groups and between the adjacent transverse rows of tufts.
